UNITED STATES PATENT OFFICE.

HARRY A. CUMFER, OF CHICAGO, ILLINOIS, ASSIGNOR TO GUYTON & CUMFER MFG. CO., A CORPORATION OF ILLINOIS.

SATURATOR.

Application filed July 22, 1921. Serial No. 486,860.

To all whom it may concern:

Be it known that I, HARRY A. CUMFER, a citizen of the United States, residing at Chicago, in the county of Cook and State of Illinois, have invented certain new and useful Improvements in Saturators, of which the following is a specification.

The invention relates to saturators.

One of the objects of the invention is to improve saturators, whereby a moving sheet of absorbent material is subjected to a saturant.

Another object is to provide a saturator for a continuously moving sheet, formed into a plurality of loops depending into a tank containing a hot saturant, and means for separately driving each loop.

Another object is to provide a saturator in which the length of the loops may independently be adjusted.

Another object is to provide a saturator in which the loop-extending roll, normally near the bottom of the tank, may be raised above the tank for ease of threading the sheet thru the saturator.

Another object is to improve the details of construction of machines of this character.

Other objects and advantages will readily appear.

30 In the drawings:—

Fig. 1 is a longitudinal view of an embodiment of the saturator showing parts in elevation and parts in section.

Fig. 2 shows parts in end elevation and other parts in transverse section.

Fig. 3 is an enlarged section taken on line 3—3 of Fig. 2.

Fig. 4 is a section taken on line 4—4 of Fig. 3.

Fig. 5 is a detail of means for raising and lowering either side of the loop so that the sheet will run true.

Fig. 6 is an enlarged view, showing parts in section of one of the loop adjusting means.

Fig. 7 is a section taken on line 7—7 of Fig. 5.

In all the views the same reference characters are employed to indicate similar parts.

In making asphaltic roofing material a continuously moving sheet of an absorbent

nature, such for example as a sheet of felt, or other similar fibrous fabric or material to constitute the base of the finished product, is saturated with a hot water-proofing material, usually of an asphaltic nature. Owing to the relatively rapid movement of the sheet thru a series of other cooperating machines, necessary for its economic production into a roofing sheet, a considerable length of the sheet must remain in the saturant a sufficient time to become thoroughly impregnated. To make a tank equal in length to the length of that part of the sheet being treated would be commercially impractical because of the improvident waste of space and the high cost of rent such an expedient would entail. Therefore, in the present machine, I form the sheet into a series of vertical loops and cause each loop to depend into a tank from a transversely disposed driven roll located near the top of the tank. Such an expedient, however, would be substantially impractical if provision were not made for conveniently threading the sheet thru the machine when the sheet becomes accidentally broken or otherwise discontinuous. To render this operation convenient I provide means for raising the loop-extending rolls to points above, or near the corresponding bodily stationary loop-driving rolls, so that the sheet will then occupy a substantially horizontal plane at the time and after it is introduced into the machine, and before being again formed into loops by lowering the loop-forming rolls.

A further refinement consists of means for adjusting the ends of each loop forming roll in order that the sheet may run true thru the saturator.

In the drawings 5 represents the tank containing the saturant, preferably located below the floor line 6. Frame members 7 and 8 extend along the sides of the tank, parallel with its sides, and slightly above the upper edge 9 of the tank. Suitably spaced apart along the frame members 7 and 8 are a plurality of pairs of roll journal bearings 10 to 14, inclusive, and supported in said bearings are rolls 15 to 19, inclusive. Each of these rolls is driven by a miter gear 20 in

mesh with a similar miter gear 21. The miter gears 20 are secured to the driving shaft 22, which is supported in a series of journal bearings 23 near each of the driving 5 miter gears 20. The rolls 10 to 18, inclusive, are driven in the same direction, clockwise as they appear to the observer in Fig. 1, but the roll 19 is driven in an opposite direction for a purpose to be hereinafter more fully 10 explained.

Two relatively adjustable receiving rolls 24 and 25 are properly supported near the front end of the machine to receive the sheet 26. These rolls are yieldingly held together 15 by mechanism adapted for the purpose of applying more or less tension to the sheet.

Near the bottom of the tank, as shown in Fig. 1, are a series of loop-extending rolls 27 to 31, inclusive. These rolls are supported at each end upon a rack structure 20 comprising two racks 128 and these racks are held together by spacing rods 129 and 130. The sheet 26 passes below each of the loop-extending rolls, as more clearly shown 25 in Fig. 1, and over the top of the respective bodily stationary rotatable driven rolls 15 to 18, respectively, and by this means each of the loops of the sheet is driven by the respectively driven rolls 15 to 18. The loop 30 flight 26', at the discharge end of the tank 5 is passed over the top of the roll 19 and then towards the front over the roll 32. The roll 32 is a pinch roll with respect to the roll 19, and these two rolls are adjust- 35 ably placed near together. The roll 32 is driven by the roll 19, and the roll 19 is driven by the bevel gears 20 and 21. These rolls serve as supplementary means for pulling the sheet through the machine.

40 A hand wheel 33 is secured to the end of the rotatable shaft 34 and by means of the bevel gears 35 and 35', the bearings containing the roll 32 are raised and lowered at both of its ends so as to increase and de- 45 crease the pressure exerted upon the sheet 26 that passes between the rolls 19 and 32, thereby to increase the frictional resistance between the rolls and the sheet to make the driving effect more positive.

50 Located on each side of the tank 5 and extending into the ground near the bottom of the tank, as at 55, are a series of pipes 36, there being a pair located mid-way between each pair of driving rolls, or one pair 55 of pipes 36 for each loop. Secured to the pipes 36, and to each pair thereof, is a bracket 37, one for each pipe, as more clearly shown in Fig. 3. The bracket is held in place by the bolt 38 which causes the ring 60 portion 39 of the bracket to intimately embrace the pipe 36. There is another pair of spaced-apart brackets 40 near the upper end 65 of the pipes 36. These brackets are similar in structure to that shown in Fig. 3, and are held on the pipes 36 in the same manner.

The rack structure 128 passes freely thru the extended ends 41 of the brackets 37 and 40. The rack structure 128 consists of a cast rack 42 having teeth 43 on one of its sides. It is preferably rectangular in cross 70 section and is contained in a tube 44 which is split, as at 45, to permit entrance of the spur gear wheel 46 to engage the rack.

A shaft 47 extends thru bearings 48 which project from the bracket 37 and the gear 75 wheels 46 are fixed to this shaft.

A hand wheel 48 is the means for turning the shaft 47 in order to raise the rack structure carrying the respective loop extending roll from the bottom of the tank to a point 80 near the upper portion thereof, for the purpose heretofore described.

The object of placing the tube 44 over the rack 42 is to strengthen the rack and to provide a uniformly even surface for passing 85 thru the guiding brackets 37 and 40 without the necessity of tooling the entire length of the rack.

Near the top of each of the pipes 36 is a bracket 49 carrying a shieve 50 on its up- 90 turned end. To each of the rack structures 42 is secured a cable 51 which passes over the sheave and is connected to a counter-weight 52 inside of each of the tubes, which is used to relieve the lifting mechanism of 95 some of the weight when it is required to raise the loop-extending rolls.

The manner of raising the loop-extending rolls, normally located near the bottom of the tank, will be clearly apparent from the 100 foregoing description when considered in connection with the drawings.

Should the sheet 26 become broken from any cause and it becomes necessary to pass 105 an unbroken sheet thru the machine it is only required that the rolls 27 to 31, inclusive, should each be raised to a point near a horizontal plane containing the driving rolls 15 to 19, inclusive, or slightly above these rolls, which may be done by rotating 110 the hand wheel 48, then the sheet is passed below the loop-extending rolls and above the relatively stationary driving rolls, whereupon the loop extending rolls, 27 to 31, inclusive, are then lowered into the tank and 115 the loops will thereby be formed. The operation described can be quickly accomplished with very little inconvenience.

Figs. 5, 6 and 7 show in detail means for 120 adjusting the height of either side of the lower portion of the loops and the respective end of the loop forming roll 129.

Located above the bracket 37 is a projection 60 held firmly on the post 36 by a strap 61. A threaded rod 62 passes freely 125 thru the projection 60 and is prevented from moving axially by the collars 63 and 64. The rod 62 is threaded at its lower end, at 65, and engages the bracket 37 at its threaded end. 130

When the bracket 37 is loosened on the posts 36 it may be raised or lowered, as required to adjust the altitude of either end of the corresponding loop-forming roll 129, 5 by rotation of the pivoted handle 66.

In practice only one side of the machine may be provided with these adjusting devices as any distortion of the loop may be corrected by either raising or lowering one 10 end of the loop forming roll 129.

While I have herein shown a single embodiment of my invention for the purpose of clear disclosure, it will be manifest to persons skilled in the art, that considerable 15 change or variation may be made in the general arrangement and configuration of the parts within the scope of the appended claims.

Having described my invention what I 20 claim as new and desire to secure by Letters Patent.

1. A saturator comprising a tank; a series of spaced-apart pairs of parallel driving rolls extending across the tank and rotatably 25 supported near the top thereof; means for rotating the rolls; parallel loop-extending rolls located in vertical planes between adjacent driving rolls and means for raising and lowering said loop-extending rolls.

30 2. A saturator comprising a tank; a series of spaced-apart pairs of parallel driving rolls extending across the tank and rotatably supported near the top thereof; means for rotating the rolls; parallel loop-extending rolls located in vertical planes between adjacent driving rolls and individual means for independently raising and lowering said loop-extending rolls.

35 3. A saturator for a moving fabric sheet comprising a tank; a series of spaced-apart pairs of parallel driving rolls extending across the tank and rotatably supported near the top thereof; means for rotating the rolls; parallel loop-extending rolls, one 40 located in a vertical plane between each pair of driving rolls; means for raising and lowering said loop-extending rolls and supplementary means at the discharge end of the tank for pulling the sheet thru the saturator.

45 4. A saturator for a moving fabric sheet comprising a tank; a series of spaced-apart pairs of parallel driving rolls extending across the tank and rotatably supported near the top thereof; means for rotating the driving rolls; parallel loop-extending rolls in vertical planes between adjacent driving rolls; means for raising and lowering each 50 loop-extending roll; a sheet tensioning means at the receiving end of the tank and supplementary driving means at the discharge end of the tank for pulling the sheet thru the saturator.

55 5. A saturator for a moving fabric sheet comprising a tank; a series of spaced-apart

pairs of parallel driving rolls extending across the tank and rotatably supported near the top thereof; means for rotating the driving rolls; parallel loop extending rolls, one located in a vertical plane between each pair 70 of driving rolls; means for raising and lowering said loop-extending rolls and counterweights tending to balance the respective loops and loop extending roll.

6. In a machine of the character described 75 the combination of a tank; a series of spaced, driven rolls near the top of the tank; means to drive said rolls in a unitary direction; a series of rolls near the bottom of the tank in vertical planes between said driven rolls; and means, above the tank, to raise and lower the lower rolls.

7. In a saturator the combination of a tank; a series of rolls mounted for rotation above the tank; means to drive said rolls; 80 a series of rolls in the tank positioned with respect to the upper rolls to lead a strip in a series of loops through the tank; and means to raise and lower the lower rolls into selected positions.

8. In a saturator the combination of a tank; a series of rolls mounted for rotation above the tank; means to drive said rolls; a series of rolls in the tank, positioned with respect to the upper rolls to lead a strip in 95 a series of loops centrally through the tank; a pair of rack bars, one at each end of each of the lower rolls, and a gear mechanism engaging said rack bars to raise and lower the respective lower roll.

9. In a saturator the combination of a tank; a series of rolls mounted for rotation above the tank; means to drive said rolls; a series of interspaced rolls in the tank, positioned with respect to the upper rolls to cause a strip formed into loops to pass centrally thru the tank; lifting bars providing 105 bearings for the lower rolls, a pair for each roll; a guide for each lifting bar; and means acting on said lifting bars to raise the respective lower roll.

10. In a saturator a tank; a series of spaced rolls mounted for rotation above the tank; a miter gear on each roll; a driving shaft common to all of said rolls having a 110 miter gear in engagement with the miter gear of each roll to drive all of the rolls in a unitary direction; a pair of posts mounted adjacent each said roll; a pair of vertically reciprocable bars guided by said posts; a roll in the tank supported on the lower ends of each pair of bars and means to simultaneously and individually raise and lower each pair of bars and the roll supported thereby.

11. In a saturator a tank; a series of spaced rolls mounted for rotation above the tank; a miter gear on each roll; a driving shaft common to all of said rolls having a 115 miter gear in engagement with the miter gear of each roll to drive all of the rolls in a unitary direction; a pair of posts mounted adjacent each said roll; a pair of vertically reciprocable bars guided by said posts; a roll in the tank supported on the lower ends of each pair of bars and means to simultaneously and individually raise and lower each pair of bars and the roll supported thereby.

12. In a saturator a tank; a series of spaced rolls mounted for rotation above the tank; a miter gear on each roll; a driving shaft common to all of said rolls having a 120 miter gear in engagement with the miter gear of each roll to drive all of the rolls in a unitary direction; a pair of posts mounted adjacent each said roll; a pair of vertically reciprocable bars guided by said posts; a roll in the tank supported on the lower ends of each pair of bars and means to simultaneously and individually raise and lower each pair of bars and the roll supported thereby.

gear of each roll to drive all of the rolls in a unitary direction; a pair of posts mounted adjacent each said roll; a pair of vertically reciprocable bars; a pair of brackets on each said post to guide said bars; a roll in the tank supported for rotation on the lower ends of each pair of bars and means,

supported on corresponding brackets of said posts to raise and lower each pair of bars and the roll supported thereby. 10

In testimony whereof I hereunto subscribed my name.

HARRY A. CUMFER.
